FREEZING UNIT FOR HOUSEHOLD
REFRIGERATORSLeland G. Knapp, Chicago, Ill., assignor to
Montgomery Ward & Co., Incorporated, Chi-
cago, Ill., a corporation of Illinois

Application October 31, 1929. Serial No. 403,693

8 Claims. (Cl. 62—95)

Heretofore it has been the general practice in constructing freezing units to provide a casing in which is mounted the expansion coils of the cooling system. The unit is then filled with alcohol, glycerine or a saline solution to aid the conduction of heat from the walls of the casing to the expansion coils. This type of unit is inefficient in that the heat conductivity of the solutions used is relatively low, with the result that it requires from four to six or seven hours to freeze water or other substances placed in the freezing compartments of the unit. Some attempts have been made to cast the expansion coils in the unit but, both from the standpoint of manufacture and operation, these attempts have not proved particularly satisfactory.

The object of the present invention is to provide a freezing unit which is highly efficient and which may be manufactured at a relatively low cost.

A further object of the invention is the provision in freezing units of a non-fluid heat-conducting medium of high efficiency.

Other objects and advantages of the invention will be obvious to those skilled in the art upon understanding the principles thereof.

For purposes of illustration there is shown, in the accompanying drawing and herein described, a preferred embodiment of the invention. It is to be understood that this disclosure is given for purposes of exemplification only as it will be obvious to those skilled in the art that many changes may be made in the device and the method of making the same without departing from the true scope and spirit of the invention as defined by the appended claims.

Referring to the drawing:

Fig. 1 is a top plan view showing in dotted lines the expansion coils mounted in the unit; Fig. 2 is a sectional view on the line 2—2 of Fig. 1 the top, however, being shown as spaced from the body of the casing; and

Fig. 3 is a sectional view on the line 3—3 of Fig. 1.

The unit comprises a casing or housing indicated in the drawing by the numeral 11 which is substantially rectangular in outline and is provided at its upper edge with a closure cap 12. Within the casing 11 and opening at the ends thereof is arranged a spaced chamber 13 which is subdivided into a plurality of freezing compartments 14. These compartments may be used to receive the usual ice trays for the freezing of ice cubes or for other purposes when a frozen product is desired. By reason of the spacing of

the chamber 13 with respect to the outer walls of the casing, spaces 15 are provided which communicate with an upper space 16 located above the chamber 13 between the top thereof and the closure cap 12. The spaces 15 and 16 receive the expansion coils 17 of the refrigerating system. These coils are of suitable length and material and are shaped to conform with the requirements of the unit.

The ends of the coils 17 have secured thereto coupling sleeves 18 which pass through openings 19 provided in the cap 12. The inner ends of the coupling sleeves are provided with flanges 20 that seat on the inner face of the cap 12 and the outer ends are screw-threaded to receive clamping nuts 21 which firmly secure the sleeves to the cap.

If it is desirable to utilize the greatest possible cooling effect of the unit in the box, fins 22 may be provided which project from the outer surfaces of the unit.

Heat-conducting material 23 consisting of a finely divided substance having relatively high heat conductivity is interposed between the coils 17 and the walls of the casing in order that the heat absorbed by the walls of the casing may be quickly and effectively removed from the unit by the action of the refrigerating medium in the expansion coils 17.

A binding medium may be used for retaining the subdivided heat-conducting material in place although such medium is not necessary. It has been found, however, that by using a binding agent which fills the interstices in the subdivided material a more efficient unit results, due to the fact that the air which would act as an insulator, is removed therefrom. A binding agent also firmly cements the coils in place and prohibits any movement thereof due to handling, vibration or other causes which might weaken them or cause their rupture.

It is desirable that the subdivided heat-conducting material be very finely divided in such form as filings or shavings, although the device is effective and fairly efficient if the heat-conducting material is in larger forms such as granules or small pieces.

Due to the high heat conductivity of the metals, such as copper, aluminum, iron, zinc, etc., they are particularly suited for the heat-conducting medium. Aluminum, having very high heat conductivity and being relatively inexpensive, is the best for practical purposes and the use of finely divided aluminum, such as in the form of filings and shavings, results in a very efficient device.

which is capable of freezing water in the freezing compartments in approximately one-half the time required in the units now generally on the market.

5 Aqueous solutions of sodium silicates which do not chemically react with aluminum or the metal used are particularly adapted for use as a binding agent as they may be had in liquid form at normal temperatures and readily permeates 10 the finely divided heat-conducting substance. A further advantage of sodium silicates of the class referred to is that by applying heat thereto the moisture may be driven off quickly and the binder reduced to a dry, hard state. The 15 hardness of the silicates when dry forms a solid block which, for all practical purposes, is indestructible. Obviously, many binding agents may be substituted for sodium silicates such as potassium silicates, shellacs, varnishes and other 20 well known materials.

The method of manufacture of the device is simple, does not require special equipment and the materials are relatively inexpensive. In assembling the device, the coils 17 are placed in 25 the casing 11 with the cap 12 removed therefrom. The subdivided heat-conducting material is poured into the casing completely covering and surrounding the coils except, possibly, portions thereof which may be in direct contact with the 30 casing. The binding agent is then poured over the heat-conducting material, permitted to percolate therethrough and is hardened. The hardening of the binding agent in the case of sodium silicates and like substances is accomplished by 35 placing the unit in an oven and raising the temperature sufficiently to drive off excess moisture. The cap 12 is then mounted on the device and secured in place.

If desirable, the cap may be placed on before 40 the hardening step provided a space is left between the edges of the cap and the casing to permit the escape of water vapors or a hole may be provided in the cap in which event the cap is secured in place and an opening left therein 45 which is subsequently filled by an ordinary screw-threaded plug.

In cases where it is desirable to freeze a large amount of material, such as ice cubes, but in which the heat to be conducted from the ice 50 box or similar equipment is less than would normally be absorbed by a unit of sufficient size to freeze the desired amount of material, the fins 22 may be omitted from the structure, and, if necessary, one of the outer walls of the casing 55 may be insulated from the coils 16 by interposing a sheet of insulated material 24 between the outer wall of the casing and coils. A convenient and effective way of providing this insulation is by pouring a layer of paraffin, wax 60 or other similar substance on the top of the finely divided heat-conducting material so that

the cap 12 is insulated from the rest of the unit.

The freezing unit herein described has been found to be highly efficient and is adapted for manufacture from relatively inexpensive materials which are quickly and easily assembled. 80

I claim:

1. A refrigerating unit comprising a casing, conduits for circulating a refrigerant within said casing, and finely subdivided aluminum interposed between said conduits and said casing, said aluminum being held in place by a binding medium. 85

2. A refrigerating unit comprising a casing, conduits for circulating a refrigerant within said casing, finely subdivided aluminum interposed between said conduits and said casing, and a binding agent consisting of sodium silicate. 90

3. A refrigerating unit comprising a casing, means for introducing a refrigerant into said casing, subdivided heat-conducting substance interposed between said last mentioned means and a portion of said casing, and a heat insulating material interposed between a portion of said heat-conducting substance and said casing. 95

4. A refrigerating unit comprising a casing, means for introducing a refrigerant in said casing, means for conducting the heat from a portion of the walls of said casing to said refrigerant, and a layer of heat insulating material positioned between one wall of said casing and said heat-conducting means. 100

5. The method of making refrigerating units which comprises placing refrigerating coils in 110 a casing, filling the casing with subdivided material, pouring a binding agent over the subdivided material and applying heat to solidify the binding agent.

6. The method of making refrigerating units which comprises placing the refrigerating coils 115 within the container therefor, filling the container and covering the coils with a subdivided heat-conducting material, pouring a binding agent in liquid form over the subdivided material permitting the same to percolate therethrough and applying heat to the unit to solidify 120 the binding agent.

7. A refrigerator cooling unit comprising spaced inner and outer shells, a coil arranged therebetween, and a filling occupying the remaining space between said shells, said filling comprising metallic particles and self-hardening binding material therefor. 125

8. A refrigerator cooling unit comprising spaced inner and outer shells, a coil arranged therebetween, and a filling occupying the remaining space between said shells, said filling comprising metallic particles and self-hardening binding material therefor having a relatively high coefficient of heat conductivity. 130
